NIPPLE EXTRACTOR OR PULLER TOOL

Martin Kalbeck, Buffalo, N. Y., assignor to Crane
Co., Chicago, Ill., a corporation of Illinois

Application November 22, 1937, Serial No. 175,808

1 Claim. (Cl. 29—88.2)

My invention relates to that type of tool useful in the removal of internally positioned radiator nipples commonly referred to as push nipples, the latter functioning to assemble individual heating 5 boiler or radiator sections in pressure-tight relation.

Heretofore, it has been a difficult and relatively expensive operation to remove the push nipples from the radiator sections during the course of 10 the disassembly thereof. The prevailing practice has been to remove them by means of hammer and chisel, and frequently such practice has obviously resulted in damage to the nipple or to the section itself to such extent that either or 15 both were not thereafter useable. Realizing that boiler and radiator sections are expensive to replace, the objection to these prior relatively harsh methods of removal of the push nipples has been serious, but apparently no practical method of 20 removal overcoming these objections has been devised prior to my invention.

It is therefore one of the principal objects of my invention to provide a more improved method 25 of removing push nipples and the like, resulting in the rapid extraction of the nipple without injury either to the radiator section or to the nipple.

Another object has for its purpose to provide a tool of this character in which the component 30 parts of the tool are assembled and held together in a compact and relatively easily operable arrangement.

Another important object lies in the provision 35 for a simple tool in which the nipple may be removed quickly by simple manipulation by relatively unskilled labor without fear of injury either to the user or to the material to which the tool is applied.

Another important advantage lies in providing 40 a tool of the character hereinafter described embodying the feature of closing or contracting the nipple chuck or puller portion of the tool in order to remove the nipple easily from the tool after the latter has been dislodged or freed from the 45 normal tapered peripheral contact with the casting.

Other objects and advantages will become more 50 readily apparent upon referring to the specification in connection with the accompanying drawings, in which preferred embodiments are disclosed and in which

Fig. 1 is an assembly view showing the tool applied to a radiator section and the like and wherein the push nipple is about to be removed, but in which the user's force to the tool has not yet been exercised.

Fig. 2 is a view similar to that disclosed in Fig. 1, except that in this view the nipple is shown as virtually withdrawn from the radiator section 55 after the necessary manual force has been ap-

plied to the tool for the removal of the push nipple.

Fig. 3 is a fragmentary sectional view showing the arrangement of the internal parts at the head or working end of the extractor tool with the bifurcated jaws of the nipple chuck being shown in the position assumed before the nipple has been withdrawn from the radiator section.

Fig. 4 is a fragmentary exterior view of the tool.

Fig. 5 is a fragmentary sectional view similar 10 to that described in connection with Fig. 3, except that the bifurcated jaws of the nipple chuck are shown in the position assumed after the nipple has been withdrawn from the radiator section.

Fig. 6 is an exterior end view of the tool described in Fig. 5.

Fig. 7 is a modified form of the tool shown in 15 partially fragmentary section.

Fig. 8 is an exterior side view of the modified 20 form of tool referred to in connection with Fig. 7.

Similar reference characters refer to similar 25 parts throughout the several views.

Referring now to Fig. 1, the radiator or boiler section is generally designated as A and, as is 30 commonly known to those skilled in the art, the individual boiler or radiator sections are assembled one with the other by means of the tapered push nipples generally referred to as B, making a pressure-tight contact with the walls of a similarly tapered aperture in the section, as indicated.

The tool consists essentially of three parts, that is a pivotable handle portion 10 having a bifurcated head and generally designated as 1, 35 an anvil or bridge member 2, and a divided nipple chuck comprising a pair of suitably shouldered pulling members 6. The anvil member 2 is connected in a manner hereinafter described in greater detail to the former by means of the flat 40 plates 3, which are affixed to each side of the anvil member 2 by the machine screws 4. Obviously, the flat plates 3 may be made integrally with the anvil or bridge member 2 without necessitating a substantial change in structure. Jour-

naled for a portion of its length within the bridge member 2 and extending through the aperture 5 thereof, the divided pulling members 6 are pivotally connected to the bifurcated head member 1 by means of the hinge pin 7, the said 45 divided members 6 being preferably maintained in spaced apart relation by means of the spiral spring 8, as shown more clearly in Fig. 3. Also 50 as shown in the latter mentioned figure, in order to provide for a positive connection between the anvil member 2 and the head 1, the flat plates 3 are provided for an interlocking coupling with each 55 side of the bifurcated head 1 by means of the pin 9 which projects from the inner surfaces of the plates 3 and which travels while maintaining 60

such connection within an arcuately extending groove 11, following closely the turning radius determined by the cam surface hereinafter described in greater detail.

5 The anvil or bridge member 2 is preferably provided with a hollow cylindrically-formed chamber 12 which is made sufficiently large and of such shape so as to easily permit the entrance of the selected size and form of push nipple B 10 sought to be removed. Obviously, the anvil member 2 may be made interchangeable and readily renewable so as to accommodate a variety of sizes of anvils with the same tool. The transverse edge and corner of the head 1 is provided 15 with a multi-directional extending curved surface 13 which functions as a cam eccentrically positioned with respect to the pivotal axis established by the pin 7 whereby upon movement of the handle 10 downwardly to the position shown 20 in Fig. 2, the surface 13 bears against the oppositely disposed surface 15 upon the member 2. For the purpose of holding the nipple securely against axial movement, the divided members 6 are provided with flanged or shouldered ends 14 25 and over which the nipple must be slipped before the extraction thereof from the section can be accomplished.

30 The groove 11, it will be noted, extends directionally so that at all points it runs parallel to the cam surface 13, and is also made sufficiently wide so that the pin 9 will not drag or bind upon the side walls of the groove.

35 In describing the operation of extracting a push nipple, let it be assumed that the nipple is mounted with relation to the radiator section A as shown in Fig. 1. The pulling members 6 are drawn together or compressed against the action of the spring 8 and are inserted as a unit together through the inner bore or aperture of the 40 nipple B, the shoulders 14 bearing against the inner walled periphery of the said aperture by the contact effected by the flanges 14. In the course of insertion, upon reaching the end of the nipple port or aperture marking also the limits of the inner portion of the radiator section A, the 45 flanges 14 will emerge from the aperture of the nipple B and thereby cause the flanges to be sprung outwardly due to the action of the spring 8. By this means, the nipple is gripped at the 50 end portion of the said aperture as more clearly shown in Fig. 1. Upon such end grip being obtained, the handle 10 of the member 1 is now moved downwardly and the cam surface 13 immediately commences to make a sliding contact 55 against the surface 15 of the anvil 2. Since the distance between the center of the pin 7 and the cam surface 13 is constantly increasing, the continued movement of such handle downwardly thereupon causes the bifurcated members 6 bearing against the end of the nipple B to be 60 pulled forward or withdrawn in view of being slidably journaled within the aperture 5.

65 Since the bridge member 2 bears rigidly against the outer portion of the radiator section A adjacent the nipple aperture, the push nipple B is dislodged from its tapered contact with the section, and thereupon continues to move axially with the pulling members 6 until ultimately, as shown more clearly in Fig. 2, the flanged ends 14 70 together with the nipple B pass within the tapered aperture of the radiator section A to the position in Fig. 2, at the end of which travel the handle of the pivoted member 1 has traveled

substantially through an arc of 90 degrees which travel, of course, may be varied. The nipple is now ready to be removed from the tool itself, and this is accomplished by simply compressing or forcing the pulling members 6 together against 5 the action of the spring, since the nipple which has now become dislodged from the section A may be easily slipped over the shoulders 14 and thus removed from the tool. For the constructions illustrated in Figs. 1 to 6 inclusive, the pin 10 9 by its travel in the grooves 11 aids merely in guiding the assembled pivotal movement of the bridge member 2 upon the cam-like surface 13 with relation to the bifurcated head 1.

15 Referring now to the modified structures shown in Figs. 7 and 8, in this construction a pivotal pin 7 similarly is mounted within a bifurcated member 1 and upon which the divided members 6 are likewise journaled. In this more simple type of construction, the bridge member 20 2 is likewise provided with a hollow cylindrical chamber 12 and bears against the upper portion thereof by means of the cam surface 13, allowing for the closing together of the bifurcated members 6 by means of the bearing effected within 25 the aperture 5. Thus when the handle 10 is moved arcuately downward, pivoting upon the hinge pin 7 and confining its entire end thrust against the upper surface 15 of the anvil member 2, the cam surface 13, for the same reason mentioned in connection with Figs. 1 to 6 inclusive, causes the divided pulling members 6 to be extracted and pulled within the aperture 5. This movement similarly causes an axial movement of the nipple outwardly or away from the section A 30 35 so as to thereupon displace the nipple B, as described in connection with Figs. 1 and 2. In this modified construction it will be noted that the guiding groove 11 and the guiding plates 3 are dispensed with, although the mode of operation 40 resulting in extraction does not differ substantially from that result described in Figs. 1 and 2.

45 It will be obvious to those skilled in this art that numerous modifications may be made within the spirit of my invention, and I desire, therefore, to be limited only to the extent of the appended claim.

I claim:

An extracting tool comprising an operating lever, a pair of shouldered end pulling members 50 in spaced apart relation, a bridge member substantially enclosing the said pulling members, the said lever having a bifurcated head pivotally attached to the said pulling members at the ends opposite the said shoulders, a pair of plates 55 secured to opposite sides of the said bridge member, the said plates having cantilever ends adjacent the said head and projecting in a plane parallel to the pivotal plane of the said head, a groove in the said head adjacent each cantilever 60 end of the said plates, a guide pin carried by the said cantilever end of each of the said plates, the said guide pin projecting transversely into the said adjacent groove whereby the said bridge member and the said head are interconnected, 65 the said head having a cam-like edge, the said bridge member having a surface in constant abutting contact with the said cam-like edge, whereby upon pivotal movement of the said lever the said pulling members are moved axially relative to the said bridge member.

MARTIN KALBECK.
